CLAIM

The ornamental design for a beverage carrier as shown and described.

DESCRIPTION

FIG. 1 is a front view of a beverage carrier showing our new design;

FIG. 2 is a rear view of the beverage carrier;

FIG. 3 is a right side view of the beverage carrier;

FIG. 4 is a left side view of the beverage carrier;

FIG. 5 is a top view of the beverage carrier;

FIG. 6 is a bottom view of the beverage carrier;

FIG. 7 is a top front side perspective view of the beverage carrier;

FIG. 8 is a top rear side perspective view of the beverage carrier shown in an environment of use; and,

FIG. 9 is a top front side perspective view of the beverage carrier shown in an environment of use.

The broken lines are illustrative of environmental structures forming no part of the claimed design.

1 Claim, 8 Drawing Sheets
